UNITED STATES PATENT OFFICE.

CHARLES J. KORINEK, OF MEDFORD, OREGON, ASSIGNOR TO KORINEK VETERINARY REMEDY COMPANY, OF MEDFORD, OREGON.

VETERINARY INSTRUMENT.

1,142,715.

Specification of Letters Patent. Patented June 8, 1915.

Application filed February 4, 1914, Serial No. 816,606. Renewed January 20, 1915. Serial No. 3,376.

To all whom it may concern:

Be it known that I, CHARLES J. KORINEK, a citizen of the United States, and a resident of Medford, in the county of Jackson 5 and State of Oregon, have invented an Improved Veterinary Instrument, of which the following is a specification.

My invention is an improvement in so-called balling irons or capsule guns which 10 are instruments employed in administering medicine, in solid form or in capsules, to horses or horned cattle, by the mouth, the same being so constructed and made of such length that the medicine may be placed in 15 the posterior part of the animal's mouth, so that it will be swallowed without mastication. Such instruments have generally been made entirely of iron, and are thus heavy, cumbersome, and difficult to use, besides 20 being objectionable for other reasons.

I have devised an improvement in instruments of this type, as hereinafter described with reference to accompanying drawing in which—

25 Figure 1 is a side view of the instrument, Fig. 2 is a longitudinal section, and Fig. 3 is a perspective view thereof, illustrating the construction of the cup or cylindrical medicine-holder, and its attachment to the 30 tubular handle.

The longitudinal, tubular body or handle 1 of the instrument is constructed of wood for sake of lightness and ease of manipulation. One end of the handle is reduced 35 and provided with a shoulder 2, as shown best in Fig. 3, and, upon the cylindrical tenon thus formed there is fitted an open-end cylinder 3, the parts being detachably secured together by means of a screw 4, as 40 shown in Figs. 1 and 2. This cylinder constitutes a so-called "cup" or medicine-holder, and a plunger consisting of a flat, circular head 5, and a metal rod 6, is arranged to slide in said cylinder and handle. 45 The outer end of the rod is provided with a loop 7, which serves as a handle for operating it. The head 5 of the plunger fits loosely in the cylinder 3 and is adapted to slide therein to the extent indicated by full 50 and dotted lines in Fig. 2. Thus, when the head 5 is drawn back against the end of the

handle tenon, the entire front portion of the holder is left free for reception of medicine in solid form or inclosed in a capsule. With the medicine so inserted, the instrument is manipulated to project the cylinder into the posterior portion of the animal's mouth, and then the rod 6 is slid forward in the handle 1, so that the head 5 forces the medicine out of the cylinder and into the 60 animal's mouth. It will be seen that the handle proper 7 of the plunger 6, comes in contact with the outer end of the handle 1, so as to limit the sliding movement of the head 5, and thus prevent it being projected 65 from the end of the cylinder 3. The end of the plunger adjacent to the disk head 5 is constructed in a flat coil to which the said head is secured, as shown. This coil comes in contact with the end of the handle when 70 the plunger is drawn back, as shown in Fig. 2. It is apparent that in constructing the implement the head 5 is first attached to the coil and the handle loop 7 is formed after the body of the plunger has been run 75 through the bore in the wooden handle 1. The coil and the handle loop thus constitute stops for the plunger, limiting its movement in both directions. The latter is made of light and duly rigid material having some 80 elasticity, so that it is not liable to injure the mouth or teeth of the horse or other animal, in administering medicine. The material I preferably employ is vulcanized 85 fiber which combines all the qualities required. It being made easily detachable from the handle 1, it may be readily removed and another substituted whenever required.

1 claim:

The improved veterinary instrument comprising a bored handle, a tubular medicine holder applied to said handle, and a plunger formed of a disk head adapted to slide in the medicine holder, and a rod having at 95 one end a flat integral coil to which said head is secured, and at the other end an integral handle loop, as described.

CHARLES J. KORINEK.
